UNITED STATES PATENT OFFICE.

JOHN C. DUEBER, OF CANTON, OHIO.

DESIGN FOR A WATCH-CASE.

SPECIFICATION forming part of Design No. 21,813, dated August 30, 1892.

Application filed July 18, 1892. Serial No. 440,412. Term of patent 14 years.

To all whom it may concern:

Be it known that I, JOHN C. DUEBER, a citizen of the United States, and a resident of Canton, county of Stark, State of Ohio, have 5 invented a new and useful Design for a Watch-Case, of which the following is a full, clear, and exact description, reference being had to the accompanying drawings, making part of this specification.

10 Figure 1 is a view in perspective of a watch-case, illustrating my invention. Fig. 2 is a view of the edge of the same.

On the lids of the case and central thereto is shown a plain circular portion A, from 15 which radiate a series of alternate grooves B and oval ribs C, increasing in breadth as they approach the perimeter of the lid, at which point is shown a small plain bead a. The bezel portion of the lid is a plain polished 20 flat bevel D, extending from the bead a to a

bead b at the outer edge of the lid. The bead b is ornamented by a series of small transverse ribs c. The rim E is a plain polished sharp oval.

The leading features of my design are the 25 radial ribs C, the plain bead a, the transversely-ribbed bead b, the flat beveled bezel D, and the plain oval rim E or edge of the case between the ribbed beads b, as shown.

What I claim, and desire to secure by Letters Patent, is—

The design for a watch-case, as herein described and shown.

In testimony whereof I have hereunto set my hand this 15th day of July, A. D. 1892.

JOHN C. DUEBER.
